RUBBER BAND GUN

Albert S. Ross, Ada, Okla.

Application February 24, 1933; Serial No. 658,408

10 Claims. (Cl. 124—14)

This invention relates to the class of toys and pertains particularly to a toy gun designed for shooting rubber bands.

The primary object of the present invention is to provide a toy gun for shooting rubber bands which is designed to be loaded with a number of bands and to shoot the same singly.

Another object of the invention is to provide a rubber band gun which may be loaded with a plurality of bands and which may be operated by a trigger mechanism to discharge the bands singly and with each discharge of a band to bring another into position for discharge when the trigger is actuated.

15 A still further object of the invention is to provide a novel barrel which serves as a magazine for the band ammunition and novel mechanism for rotating the barrel whereby to bring into position for discharge a new band after one has 20 been released.

Other objects and advantages of the invention will become apparent as the description of the same proceeds and the invention will be best understood from a consideration of the following 25 detailed description taken in connection with the accompanying drawings forming part of this specification, with the understanding, however, that the invention is not confined to any strict conformity with the showing of the drawings but 30 may be changed or modified so long as such changes or modifications mark no material departure from the salient features of the invention as expressed in the appended claims.

In the drawings:—

35 Figure 1 shows the gun embodying the present invention in side elevation;

Figure 2 is an enlarged vertical sectional view taken longitudinally through the breech portion of the gun;

40 Figure 3 is a sectional view similar to Figure 2 but showing the trigger mechanism retracted for the discharge of a band;

Figure 4 is a vertical sectional view taken longitudinally of the muzzle end of the gun;

45 Figure 5 is a transverse sectional view taken substantially upon the line 5—5 of Figure 2, certain of the elements falling within the plane of the section line being in elevation;

50 Figure 6 is a sectional view taken substantially upon the line 6—6 of Figure 5;

Figure 7 is a view in elevation of the rear end of the barrel;

55 Figure 8 is a view in perspective of a spring latch pin forming a part of the trigger mechanism;

Figure 9 is a sectional view taken substantially upon the line 9—9 of Figure 4;

Figure 10 is a view in front elevation of a portion of the trigger mechanism removed from the breech;

Figure 11 is a perspective view of an element of the trigger mechanism by which a spring latch is actuated;

Figure 12 is a view in perspective of the rear head of the barrel;

Referring now more particularly to the drawings wherein like numerals of reference indicate corresponding parts throughout the several views, the numeral 1 indicates the stock of the present gun, while the breech portion is indicated by the numeral 2. Extending forwardly from and detachably secured to the lower part of the breech by the transverse pins 3 is a barrel supporting arm 4 at the rear end of which the trigger guard 5 is formed. At the forward end of the arm 4 there is formed the upwardly extending terminal 6 in the rear face of which is formed a bore 7 for the reception of one end of the pin member 8.

In the forwardly facing wall of the breech 2 there is formed the chamber 9 which opposes the rear wall of the upstanding portion 6 of the arm 5 and secured in a suitable bore 10 in the body of the breech is one end of a pin 11 which extends forwardly through the chamber 9 and a short distance beyond the forward face of the breech as shown in Figures 2 and 3. This pin 11 is aligned with the pin 8 at the forward end of the arm.

Located above the arm 5 between the forward face of the breech 2 and the rear face of the upstanding portion 6 of the arm is a barrel which is indicated as a whole by the numeral 12. This barrel comprises a cylindrical portion 13 which at its forward end is closed by the forward head block 14 which is provided with the axial passage 15 in which the rear end of the pin 8 engages. Secured in this head 14 in any suitable manner is a plurality of pins 16 which extend from the outer face of the head as shown in Figure 4. The pin 8 between the head 14 and the portion 6 of the arm carries a sleeve 17 which acts as a spacing means between the head and the portion of the arm referred to.

The rear end of the barrel cylinder 13 has fitted thereinto an end of the circular rear head 18. This head is provided at its forward end which is fitted into the cylinder 13 with the axial chamber 19 into which opens the axial bore 20 formed in the head from the opposite end. In this bore 20 the forward end of the pin 11 engages and as

will be readily apparent the barrel 12 is, therefore, rotatably mounted upon this pin and the forward pin 8.

The rear end of the head 18 has cut thereinto the longitudinally extending slots 21 which open through the outer surface of the head and through the rear end thereof as shown in Figures 2 and 12. The forward ends of these slots open into the chamber 19 and the number of these slots 21 correspond to the number of pins 16 which are carried by the forward head 14. Also, the slots 21 are each in alignment longitudinally of the barrel with a pin 16.

The head 18 is provided in its outer surface with the circumferential channel or groove 22 in which is tightly fitted a wire ring or annulus 23 and this groove 22 is so located that the annulus 23 passes over the slots 21.

Oscillatably mounted in each of the slots 21 and upon the annulus 23 is a band holding finger 24 which projects radially beyond the outer surface of the head 18 as shown in Figures 2 and 3.

Disposed longitudinally of the head 18 within the chamber 19 is a series of spring latch pins indicated as a whole by the numeral 25. Each of these pins is preferably rounded at its rear end and throughout a portion of its length as indicated at 26 and at its other end there is formed the right angularly turned terminus 27 which is flattened as shown in Figure 8 and provided with a screw-threaded aperture 28. The portion of each latch pin 25 lying between the end 26 and the end 27 is relatively thin and spring-like in character as indicated at 29.

The spring latch pins 25 correspond in number with the band holding fingers 24 and each has its flattened terminal portion 27 secured by a screw 30 to the inner or forward end of the rear head 18 with the spring-like intermediate portion 29 extending through the chamber and into a recess 21, with the rear end 26 projecting from the rear of the recess as shown in Figure 2. These rear end portions 26 of the spring latch fingers extend into the chamber 9 of the breech and are engaged by elements of the trigger mechanism of which they form a part.

The inner end of the portion 26 of each latch pin 25 constitutes a latch shoulder which is indicated by the numeral 31 and the rear inner corner of the adjacent band holding finger 24 normally engages this latch shoulder and is held thereby in the normal outwardly directed position in which it is illustrated in Figure 2. In addition, each of these fingers is assisted in retaining this position by a spring 32 which has one end attached to the finger while the other or forward end is secured in a convenient manner as, for example, to the laterally turned portion 27 of the latch pin, in the manner shown.

Formed in the lower part of the breech 2 is a chamber 33 which opens into and forms a part of the chamber 9 and the opening 34 provides a means for the gun trigger to extend from the chamber 33 into the area of the guard 5.

Upon the pin 35 which extends transversely through the gun breech and through the chamber 33 is mounted the trigger member 36 which extends through the opening 34 into the guard 5 in the manner shown and integral with the pivoted end of this trigger is an arm 37 which extends forwardly and terminates in the lower part of the chamber 9. Spring means, such as that indicated by the numeral 38, normally urges the trigger 36 to swing forwardly to the position in which it is shown in Figure 2.

The arm 37 is bifurcated at its forward end and the furcations are connected by a pin 39. Disposed between these furcations is the downwardly directed tail-piece 40 of a trip block 41 which stands uprightly in the chamber 9 and has the elongated vertical opening 42 for the extension of the pin 11 therethrough. The tail-piece 40 of the trip block is also provided with a vertically disposed elongated slot which is indicated by the numeral 43 and through which the pin 39 passes.

Upon its upper end the trip block 41 carries the forwardly extending trip finger 44 which is disposed upon the vertical longitudinal plane of the barrel 12 and normally overlies the end 26 of a spring latch pin 25, being held and supported in this position by the pin 39 of the trigger arm.

As shown in Figure 10 the pin 39 is extended at one end a substantial distance beyond the arm 37 and upon this extended end is oscillatably mounted the barrel actuating finger 45, the pin 35 passing through one end thereof. The other end of this finger is cut out to form a vertical abutment face 46 and a lip 47 which extends forwardly therefrom. The under face of this lip is shaped to form the concave cam surface 48. A spring member 49 which is here illustrated as being carried upon the pin 35, engages and normally urges the free upper end of the vertically disposed barrel revolving finger 45 forwardly.

In the bottom part of the chamber 9 there is pivotally mounted intermediate its ends upon the vertical retaining screw 50 the bar 51. One end of this bar 51 has a loose connection 52 with a barrel locking pin 53 which is reciprocably mounted in a suitable bore 54 formed in the breech 2 and opening through the forward face thereof. This structure is illustrated in Figure 6 and as is also clearly shown in this figure a coil spring 55 is housed in the bore 54 behind the pin 53 and normally urges the same outwardly where it may engage its forward end in one of the recesses 21 of the rear barrel head 18 to hold the barrel against rotation. The end of the bar 51 which is connected with the barrel locking pin 53 is remote from the end nearest the barrel rotating finger 45 as is shown in Figure 6.

In the operation of the present gun the same is loaded by engaging over each of the pins 16 at the forward end of the barrel 12, one end of a rubber band 56 and stretching the same rearwardly until its other end may be engaged over a corresponding finger 24. This will tend to draw or oscillate the finger forwardly against the tension of the holding spring 32 and if the finger 24 were not otherwise held the spring 32 would be of insufficient strength to prevent the finger oscillating under the influence of the band and the band would, therefore, have its rear end released. However, the inner corner of the finger 60 is engaged against the latch shoulder 31 of the spring latch pin 25 and, therefore, firmly held against movement.

As previously stated the trip finger 44 of the block 41 normally overlies the rear end 26 of the uppermost or highest one of the pins 25 and from this it will be readily apparent that when the trip block 45 is pulled down the finger 44 will operate to spring the rear end of the latch pin downwardly so as to release the finger 24 which it normally holds. This release of the finger 24 is effected by oscillating the trigger 36 and after a period of idling movement insofar as the trip block 41 is concerned, the pin 39 will reach the bottom of the slot 43 in the tail-piece of the trip

block and it will then engage and pull the block down for the discharge of the rubber band in the manner set forth.

As will be seen upon reference to Figure 5 the barrel rotating finger 45 is disposed at one side of the longitudinal center of the gun and, as shown in Figure 2, its cam surface 48 overlying the rear end of a spring latch pin so that during the initial movement of the trigger 36 and the swinging downward of the arm 37 before the trip lock 41 is moved, the surface 48 will cam against the underlying pin 25 and swing the finger 45 backwardly against the tension of the spring 49 as illustrated in Figure 3. At the same time the finger 45 is moving across the free end of the bar 51 but due to the fact that it is swinging backwardly it does not affect the bar.

However, a point is reached in the movement of the finger 45 where the forward edge of the lip 47 rides over the end of the pin 25 with which the cam surface 48 has been in engagement, whereupon the spring 49 snaps the arm 45 forwardly bringing the abutment surface or wall 46 against the end of the adjacent pin 25 and at the same time delivering a sharp blow upon the free end of the bar 51. Simultaneously with this action the trip finger 44 effects the release of the adjacent finger 24 and the rubber band held thereby. The blow delivered to the bar 51 swings rearwardly the end attached to the pin 53 and thus releases the barrel 12 so that when the trigger 36 is released and the spring 38 becomes effective to swing the trigger back to its normal position the barrel rotating finger 45 will be forced to move upwardly and the lip 47 thereof will engage under the adjacent pin 25 and impart sufficient rotary motion to the barrel to bring another rubber band holding finger 24 into the position where the spring latch pin 25 holding it has its rear end located beneath the trip finger 44. At the same time a recess 21 comes into position to receive the barrel locking pin 53 and the gun is then ready for the discharge of another band.

From the foregoing it will be readily apparent that a rubber band shooting gun constructed in accordance with the present invention may be made to carry any desired number of bands by increasing or decreasing the number of slots 21 in the rear barrel head 18 and the parts associated therewith and also correspondingly increasing or decreasing the number of pins 16 upon the forward head. With a gun of the character herein set forth the full capacity of bands may be shot without giving any attention to the gun other than to operate the trigger in the customary manner.

Having thus described the invention, what is claimed is:—

1. A rubber band gun, comprising a stock having a breech, an arm extending forwardly from said breech, an elongated member rotatably supported at its ends between the breech and the forward end of said arm, coating elements at the ends of said elongated member for holding rubber bands in stretched condition and disposed longitudinally of the member, the elements adjacent the breech being adapted to be shifted for the release of the bands connected therewith, shiftable means normally holding said elements against movement by the tensioned bands and trigger actuated means normally restraining said means from movement by the band connected therewith, and releasing the latter when and as

the elements are brought to a predetermined position by the rotation of the band carrying member.

2. A gun of the character described, comprising a stock having a breech, an arm carried by the stock and having an angularly extended forward end, a barrel disposed between the breech and said arm end, means pivotally supporting the ends of the barrel upon the breech and the adjacent end of the arm, pin members mounted in the forward end of the barrel and extending longitudinally thereof each being designed for engagement by a rubber band, a plurality of oscillatably mounted elements carried by the barrel at its rear end and corresponding in number with the pins and further extending radially of the barrel, the oscillatable elements being designed to have the other ends of the stretched rubber bands engaged therewith, means normally retaining said elements against oscillation, a trigger oscillatably mounted in the breech, and a trip element actuated by said trigger for releasing the oscillatable elements as each is brought to a predetermined position by the rotation of the barrel.

3. A gun comprising a stock having a breech, an arm carried by the breech and extending forwardly therefrom, a barrel extending forwardly from the breech over said arm, means pivotally connecting the ends of the barrel with the breech and the arm, the end of the barrel adjacent the breech having a plurality of radial recesses therein each opening through the adjacent barrel end, a plurality of fingers each oscillatably mounted in a recess, a resilient latch pin for each of said fingers and normally holding the same against oscillation, each of said fingers being designed to have an end of a rubber band engaged thereover, means at the forward end of the barrel for holding the other ends of the rubber bands in stretched condition, a trigger mounted in the breech, an element in the breech actuated by the trigger for shifting an adjacent spring latch pin for the release of the finger held thereby, and means for effecting the rotation of the barrel to progressively bring the latch pins into position for engagement by the trigger actuated element.

4. A gun comprising a stock having a breech, an arm carried by the breech and extending forwardly therefrom, a barrel extending forwardly from the breech over said arm, means pivotally connecting the ends of the barrel with the breech and the arm, the end of the barrel adjacent the breech having a plurality of radial recesses therein each opening through the adjacent barrel end, a plurality of fingers each oscillatably mounted in a recess, a resilient latch pin for each of said fingers and normally holding the same against oscillation, each of said fingers being designed to have an end of a rubber band engaged thereover, means at the forward end of the barrel for holding the other ends of the rubber bands in stretched condition, a trigger mounted in the breech, an element mounted for vertical reciprocation in the breech and adapted when shifted in one direction to engage a latch pin for the release of the oscillatable band holding finger held thereby, connecting means between said element and the trigger, means actuated by the trigger when shifted in one direction for imparting a partial rotary movement to the barrel, and means normally locking the barrel against movement which is released by and prior to the operation of the barrel shifting means.

5. A gun of the character described, comprising a stock having a breech, an arm carried by and extending forwardly from the breech, a barrel disposed longitudinally of the arm and having one end pivotally connected with the breech and the other end pivotally connected to the arm, a plurality of fingers disposed about the barrel at the rear end and extending radially therefrom, means for pivotally supporting said fingers, each of said fingers being designed to hold one end of a stretched rubber band, means at the forward end of the barrel for holding the other ends of the stretched bands, an oscillatable resilient latch pin for each of said oscillatable fingers, disposed within the barrel and normally engaging and holding the adjacent finger against oscillation, a trigger pivotally mounted in the breech, an arm carried by the trigger, a trip member mounted for vertical movement in the breech and having a finger normally overlying a latch pin, a loose connection between said trip member and said trigger arm, a finger carried by the trigger arm and normally resiliently forced forwardly and adapted to ride over the end of a latch pin upon the actuation of the trigger in one direction for engagement beneath the pin, a spring pressed pin normally locking said barrel against rotary movement, and an oscillatable element connected with said spring pressed pin, said spring pressed trigger arm carrying finger operating against said oscillatable element to retract the last mentioned pin and the trigger arm carrying finger engaging beneath an adjacent latch pin and imparting rotary movement to the barrel therewith upon return of the trigger to normal position.
6. A gun comprising a stock having a breech, an arm carried by the breech and extending forwardly therefrom, a barrel extending forwardly from the breech over said arm, means pivotally connecting the ends of the barrel with the breech and the arm, the end of the barrel adjacent the breech having a plurality of radial recesses therein each opening through the adjacent barrel end, a plurality of fingers each oscillatably mounted in a recess, a resilient latch pin for each of said fingers and normally holding the same against oscillation, each of said fingers being designed to have an end of a rubber band engaged thereover, means at the forward end of the barrel for holding the other ends of the rubber bands in stretched condition, a trigger mounted in the breech, and an element in the breech actuated by the trigger for shifting an adjacent spring latch pin for the release of the finger held thereby.
7. In a gun of the character described, a rotatably supported barrel having a plurality of radial slots in one end, an element oscillatably mounted in each slot and projecting therefrom, each of said elements being designed for engagement by a resilient body constantly tending to oscillate it in one direction, resilient means engaging each element and resisting the tendency of the latter to oscillate in the said one direction, a plurality of elongated resilient fingers disposed longitudinally in the barrel and each having a shoulder engaging and holding an oscillatable element against movement, said fingers being resiliently mounted to swing inwardly of the barrel, a trip finger reciprocably mounted adjacent the end of the barrel in which said elements are carried and adapted when shifted in one direction to engage and move a resilient finger to effect the release by the latter of a pivotally mounted element, and a trigger pivotally mounted adjacent to and having connection with said trip finger, said oscillatable elements being restored to latched connection with the resilient fingers by the second mentioned resilient elements connected therewith after being oscillated for the release of the first mentioned resilient elements connected therewith.
8. In a gun of the character described, a stock and a breech body, a barrel rotatably connected with and extending from said breech, a plurality of elements oscillatably mounted on the barrel adjacent the breech and projecting radially from and beyond the outer face of the barrel, means at the forward end of said barrel facilitating connection of resilient elements of the nature of rubber bands between said forward end and said elements, resilient means within the barrel connected with each of said oscillatable elements and tending to oscillate the elements to said radially projecting positions, a plurality of restraining elements secured to said barrel and each engaging an oscillatable element to hold the same in set position, each of said restraining elements being adapted to be shifted inwardly for the release of the oscillatable element, a trigger carried by the breech, and a reciprocable finger connected with the trigger for actuation thereby and in the path of movement of which the restraining elements are successively moved by the rotation of the barrel.
9. In a gun of the character described, a stock and breech body, a barrel rotatably connected with and extending from said breech, a plurality of elements oscillatably mounted on the barrel adjacent the breech and projecting radially from and beyond the outer face of the barrel, means at the forward end of said barrel facilitating connection of resilient elements of the nature of rubber bands between said forward end and said elements, resilient means within the barrel connected with each of said oscillatable elements and tending to oscillate the elements to said radially projecting positions, a plurality of restraining elements secured to said barrel and each engaging an oscillatable element to hold the same in set position, each of said restraining elements being adapted to be shifted inwardly for the release of the oscillatable element, a trigger carried by the breech, a reciprocable finger connected with the trigger for actuation thereby and in the path of movement of which the restraining elements are successively moved by the rotation of the barrel, and means connected with and actuated by the trigger when the latter is shifted in one direction, to impart sufficient rotary movement to the barrel to dispose a restraining element in the path of movement of said finger.
10. In a gun of the character described, a stock and breech body, a barrel rotatably connected with and extending from said breech, a plurality of elements oscillatably mounted on the barrel adjacent the breech and projecting radially from and beyond the outer face of the barrel, means at the forward end of said barrel facilitating connection of resilient elements of the nature of rubber bands between said forward end and said elements, resilient means within the barrel connected with each of said oscillatable elements and tending to oscillate the elements to said radially projecting positions, a plurality of restraining elements secured to said barrel and each engaging an oscillatable element to hold the same in set position, each of said restraining elements being adapted to be shifted inwardly for the release of the oscillatable element, a trigger carried by the breech, a reciprocable finger connected with the trigger for actuation thereby and in the path of movement of which the restraining elements are successively moved by the rotation of the barrel.

trigger for actuation thereby and in the path of movement of which the restraining elements are successively moved by the rotation of the barrel, means connected with and actuated by the trigger when the latter is shifted in one direction, to impart sufficient rotary movement to the barrel to dispose a restraining element in the path of

movement of said finger, shiftable locking means for the barrel, and means operated by and simultaneously with the release of a restraining member for actuating the shiftable locking means in a direction to release the barrel for rotation. 5

ALBERT S. ROSS.
